[57] CLAIM

The ornamental design for the battery for a portable two-way radio, as shown and described.

DESCRIPTION

FIG. 1 is a front and left side perspective view of a battery for a portable two way radio showing our new design;

FIG. 2 is a right side elevational view thereof;

FIG. 3 is a rear elevational view thereof; and

FIG. 4 is a bottom plan view thereof.

The radio is shown in broken lines for illustrative purposes only, and forms no part of the claimed design.
